DATE SETTING DEVICE

Albert S. Wheelbarger, Dayton, Ohio, assignor
to Ohmer Fare Register Company, Dayton,
Ohio, a corporation of Ohio

Application February 25, 1927. Serial No. 170,981

11 Claims. (Cl. 101—110)

This invention relates to an improved date setting device to be used in ticket-issuing machines, cash registers, and other devices wherein it is desired to print the date of a transaction. Heretofore the date printing wheels have been set by manually rotating each one of the wheels separately. My invention relates to means whereby a suitable tool such as a key may be used to rotate the month and date wheels without the necessity of the operator soiling his hands.

Another object of the invention is to overcome the objection that where the wheels are rotated separately the hand of the operator will probably overlap two of the printing wheels, rotating both of them when he desired to rotate only one. The day printing wheels are generally made as two separate parts, one of which contains the numerals 0 to 9 inclusive and the other the numerals 1 to 3 inclusive. The month printing wheel has also been made as a separate wheel. I do not propose to change this arrangement for to do so would require very large wheels which is not desirable. I do seek, however, to overcome the objection of rotating any of the printing wheels which should not be adjusted to change the date from, for instance, the 3rd to the 4th.

My invention also relates to means to visually indicate on the outside of the machine what is the setting of the printing wheels on the inside of the machine. In setting the printing wheels the operator need only observe the visual indicator on the outside of the machine which instantly shows the date that the printing wheels are then set to print.

Obviously many changes may be made in the specific embodiment shown herein by way of illustration without departing from the spirit of the invention. I, therefore, intend in the attached drawing and the detailed specification to illustrate only the preferred embodiment of the invention, reserving to myself the right to make changes and modifications which may fairly fall within the spirit of the inventive idea and within the broad terms of the claims at the end of the specification.

In the drawing:

Fig. 1 is a side elevational view,

Fig. 2 is a plan view partly in cross section,

Fig. 3 is a cross-sectional view on the line 3—3 of Fig. 2 looking in the direction of the arrows, and

Fig. 4 is a view of the conductor's key or the instrument to operate the date setting device.

Referring more particularly to the drawing,

the frame 1 of the machine is provided with a number of cross bars 2, of which only one is shown in the drawing, and a secondary frame 3 is secured to the cross bars 2. A shaft 4 is rotatably mounted in the frame members 1 and 3, which shaft 4 is provided at its outer end with a substantially rectangular aperture 5 adapted to receive the end 6 of the key 7. The key 7 performs two functions. First, it is a printing key having type 8 which key is inserted within the opening 9 in the frame 1 so that the type 8 will be in alignment with the printing wheels hereinafter described, and secondly, it may be removed from the opening 9 and inserted in the opening 5 and thereby serve as a means to turn the shaft 4. The shaft 4 carries a collar 10 secured thereto by means of a pin 11, which collar carries a ten-toothed gear 12, which meshes with and drives a 40-toothed gear 13, which gear 13 is provided with a disk 14 having the days of the month from 1 to 31 inclusive thereon as is shown in Fig. 1. The gear 13 is provided with a rearwardly extending tapering hub 15. The hub 15 receives a sleeve 16 mounted on a shaft 17 secured to the frame 1. The sleeve 16 carries a disk 18 on which the months are inscribed, as is shown in Fig. 1, and also carries a gear 19 which meshes with an idler gear 20 rotatably mounted on the frame 1, which gear 20 is actuated by means hereinafter to be described.

The shaft 4 carries a sleeve 21 secured thereto by means of a pin 22, which sleeve 21 carries a ten-toothed gear 23 and a one-toothed disk 24. The gear 23 meshes with a ten-toothed gear 25 rotatably mounted on a shaft 26. The gear 25 carries a printing disk 27 having numerals 0 to 9 inclusive on its periphery. The printing disk 27 is the disk which prints the units of the days, for instance, the 7 of 27. The one-toothed disk 24 drives a swiss gear 28 which swiss gear has secured thereto a tens printing wheel 29 and a Geneva disk 30 having as many teeth thereon as there are sets of indications on the wheel 29. The tens printing wheel 29 is provided with two or three sets of characters, being blank 1, 2, 3. The Geneva disk 30 drives a swiss gear 31 which is integral with a toothed gear 32 which meshes with and drives a toothed gear 33 on the shaft 26, which gear 33 is secured to the months printing wheel 34. The year printing wheel 35 is manually operated and forms no part of this invention.

The gears 23 and 32 are held in adjusted position by means of a holding arm 36 in the form of a lever 37 pivoted on the shaft 2 and tensioned by means of a spring 38. The swiss gear 28 is

also held in set position by means of an arm 39 pivoted on the shaft 2 and having a depending portion similar to the part 37.

The toothed gear 32 is rigidly secured to a sleeve 40 which carries a toothed gear 41 which meshes with and drives the gear 20.

In operation, let us assume that the parts are in the position shown in Fig. 1; that is, the printing disks 27, 29 and 34 are set to print Oct. 13 and the visual disks 14 and 18 show the same date, it being understood that the date to read on the disks 14 and 18 is on the horizontal line extending to the right from the center of same. The date may be changed to Oct. 14 by inserting the key 7 in the aperture 5 and rotating the same clockwise, until the "14" has been brought into the position in alignment with the word "Oct.". This, of course, is accomplished directly through the gears 12 and 13, at the same time, however, the gear 23 has been rotated one tooth so that the units printing wheel 27 is simultaneously set with the disk 14. Each day this simple operation is repeated. On changing from 19 to 20, or from 9 to 10, or 29 to 30, it is necessary to rotate the tens printing disk 29 one step which is accomplished by means of the one-toothed disk 24 engaging the swiss gear 28. This is an ordinary transfer mechanism and requires no particular description. Hereinafter the printing wheels 27 and 29 are referred to as the date printing wheels and the disk 14 as the indicating disk, in contradistinction to the month printing wheel and indicating disk. After the disk 14 has been rotated until the days of that month have been past, the key 7 is rotated until the number "1" appears in correct position. If the month, for instance, were January, which has 31 days, it would be necessary to rotate the key 7 nine spaces in order to set the mechanism for February 1. To change from February to March would require a rotation of twelve spaces, being the difference between 40 and 28, the gear 13 having 40 teeth thereon. While this is taking place the gear 23 is constantly rotating the gear 25 and the one-toothed disk 24. When the printing wheels 27 and 29 indicate the number "39" a further rotation will actuate the month printing wheel 34 through the one-toothed disk 24, swiss gear 28 and toothed disk 30, driving the swiss gear 31, the toothed gear 32, and the toothed gear 33, rotating the printing disk 34 one-twelfth of a revolution or the distance between two successive months. While at the same time the gear 32 has rotated the sleeve 40, gears 41, 20 and 19, thereby rotating the disk 14 one-twelfth of a revolution. The reason that a plurality of teeth are placed on the disk 30 is that there are a plurality (2 or 3) sets of numbers 0 to 3 inclusive on the tens printing wheel 29. Such a construction avoids the necessity of continuing to rotate the mechanism until the tens printing wheel 29 had been rotated to 9, as would be necessary if the disk 30 were provided with a single tooth.

It is, therefore, obvious that by my improved structure the mechanism moves synchronously so that the operator can set any date whatsoever by inserting the key 7 in the aperture 5 and turning it until the desired date appears on the disks 14 and 18. Furthermore, the holding arms 36 and 39 retain the mechanism in its set position so that the printing mechanism cannot rotate these wheels and thereby destroy the correct setting of the same.

Having now described the preferred embodiment of my invention I claim:

1. In a machine of the type described, units and tens printing wheels for dates, a disk to visually indicate the setting of said wheels, operative means interconnecting said wheels and disk and means whereby said wheels and disk may be adjusted to any desired indication. 80

2. In a machine of the type described, units and tens printing wheels for dates located within the machine, a disk located without the machine to visually indicate the setting of said wheels, and operative means interconnecting said wheels and said disk. 85

3. In a machine of the type described, a unit of days printing wheel, a tens of days printing wheel, a month printing wheel, and a common setting means for all of said wheels. 90

4. In a machine of the type described, a units printing wheel having indications 0 to 9 inclusive on its periphery, a tens printing wheel having sets of indications 0 to 3 inclusive on its periphery, a month printing wheel carrying indicia to represent the twelve months of the year, and a common setting means for all of said wheels. 95

5. In a machine of the type described, date and month printing wheels, a disk to visually indicate the setting of the date printing wheels, a second disk to indicate the setting of the month printing wheels, and a common setting means for all of said wheels and disks. 100

6. In a machine of the type described, date and month printing wheels, concentric disks having indicia thereon to indicate the setting of the said wheels, and means interconnecting all of said wheels and disks. 105

7. In a machine of the type described, concentric disks to indicate the month and date, said date indicating disk being provided with forty spaces and said month indicating disk being provided with twelve spaces, and means interconnecting said disks so that the month indicating disk is moved one space after the date indicating disk has been rotated one complete revolution. 115

8. In a mechanism of the kind described, a shaft, a gear and a one-toothed disk secured thereto, date printing wheels actuated by said gear and disk, a Geneva disk secured to the date printing wheel which is actuated by the one-toothed disk, a collar rotatably mounted on said shaft, a gear secured to said collar and actuated by said Geneva disk, toothed gear secured to said collar, a month printing wheel, and a gear secured to said month printing wheel and meshing with said last mentioned gear. 120

9. In a machine of the class described, a shaft, a gear rigidly secured thereto, a visual indicator actuated by said gear to indicate the days of the month, a ten-toothed gear and a one-toothed disk secured to said shaft, printing wheels to indicate the day of the month actuated by said ten-toothed gear and one-toothed disk, a Geneva disk secured to the date printing wheel actuated by the one-toothed disk, a collar rotatably mounted on said shaft, a swiss gear and two toothed gears secured to said collar, a month printing wheel, a gear carried thereby and meshing with one of the last mentioned gears on said collar, a month indicating disk, and a gear secured thereto and driven by the other of said gears on said collar. 130

10. In a machine of the class described, a shaft, a gear rigidly secured thereto, a visual indicator actuated by said gear to indicate the days of the month, a ten-toothed gear and a one-toothed disk secured to said shaft, printing wheels to 140

145

150

indicate the day of the month actuated by said ten-toothed gear and one-toothed disk, a Geneva disk secured to the date printing wheel actuated by the one-toothed disk, a collar rotatably mounted on said shaft, a swiss gear and two toothed gears secured to said collar, a month printing wheel, a gear carried thereby and meshing with one of the last mentioned gears on said collar, a month indicating disk, a gear secured thereto and driven by the other of said gears on said collar, and holding and aligning means

to prevent accidental rotation of said printing wheels.

11. In a machine of the type described, units and tens printing wheels for dates, a disk to visually indicate the setting of said wheels means to operate manually said wheels, operative means interconnecting said wheels and disk, and means to prevent the accidental rotation of said wheels and disk. 80

CERTIFICATE OF CORRECTION.

Patent No. 1,947,893.

February 20, 1934.

ALBERT S. WHEELBARGER.

It is hereby certified that the State of Incorporation of the assignee in the above numbered patent was erroneously given as "Ohio", whereas said State should have been given as New York, as shown by the records of assignments in this office; and that the said Letters Patent should be read with this correction therein that the same may conform to the record of the case in the Patent Office.

Signed and sealed this 25th day of May, A. D. 1937.

(Seal)

Henry Van Arsdale
Acting Commissioner of Patents.
